UNITED STATES PATENT OFFICE.

PHILIP G. LUCAS, JR., OF ST. LOUIS, MISSOURI.

DESIGN FOR A MINNOW-BUCKET OR SIMILAR ARTICLE.

50,755.

Specification for Design.

Patented May 8, 1917.

Application filed November 13, 1915. Serial No. 61,423. Term of patent 14 years.

To all whom it may concern:

Be it known that I, PHILIP G. LUCAS, Jr., a citizen of the United States, residing at St. Louis and State of Missouri, have invented a new, original, and ornamental Design for a Minnow-Bucket or Similar Article, of which the following is a specification, reference being had to the accompanying drawing, forming part thereof.

Figure 1 is a front elevation showing this improved minnow bucket.

Fig. 2 is a left hand end elevation of Fig. 1.

Copies of this patent may be obtained for five cents each, by addressing the "Commissioner of Patents, Washington, D. C."

Fig. 3 is a right hand end elevation of Fig. 1.

This invention relates to the production of a new and original design for minnow buckets in which the perforated portions are formed in the ends of the lid.

I claim:

The ornamental design for a minnow bucket or similar article, as shown.

PHILIP G. LUCAS, Jr.
